DRAFT GEAR MOUNTING

Robert M. Nelson, Evanston, Ill., assignor to Peerless Equipment Company, Chicago, Ill., a corporation of Delaware

Application March 7, 1940, Serial No. 322,797

5 Claims. (Cl. 213—31)

This invention relates to draft gears for rail-way cars.

Draft gears of specifically different designs are in use and some of them may be used interchangeably in a certain draft gear pocket of a car under-frame structure without requiring alterations to said pocket, while others can be used in said certain draft gear pocket only if the same is altered to accommodate them.

It is very undesirable to have to alter the draft gear pocket of a car under-frame structure to accommodate any given draft gear. On the other hand, it is desirable in many instances to use in association with a certain draft gear pocket a draft gear which, as heretofore constructed, could be used with the said pocket only if the latter is altered.

Accordingly, the general object of the present invention is to provide adapter means whereby certain draft gears which, as heretofore constructed, cannot be used in a certain draft gear pocket of a car under-frame structure, except by altering the draft gear carrier plate, may readily be adapted for use with said draft gear pocket without any necessity of altering the carrier plate.

There is a decided modern trend toward reducing the weight of car structures generally, and in accordance with this trend, as well as to save metal and reduce production costs, it is desirable that draft gear assemblies be maintained as light in weight as practicable. Accordingly, another object of the present invention is to provide adapter means for the purpose stated which is not a permanent part of any draft gear with which it may be associated, but which is separate therefrom and attachable thereto and detachable therefrom at will, whereby it need not be used in any instance where its use is unnecessary, and whereby its weight is added to the normal weight of the gear only in instances where its use is necessary to adapt the gear for use in a certain pocket structure.

Another object of the invention is to provide simple means for detachably mounting the adapter means on that part of a draft gear with which it is intended for use, namely, the casing of the draft gear, and for holding it securely in operative assembly with said casing when it is attached thereto.

Adapter means for the purpose stated is particularly intended for use in association with draft gears employing horizontal yokes. However, it may be desirable in many instances to use in association with a vertically disposed yoke

a draft gear which is constructed to have said adapter means applied thereto. In such instances there is no necessity of using the adapter means and, of course, it is not used. In this connection another object of the invention is to provide a draft gear embodying a special construction adapting it to have attached thereto adapter means for the purpose stated, and according to which said special construction does not in any way interfere with use of the gear in association with a vertically disposed yoke.

With the foregoing and other objects in view, which will become more fully apparent as the nature of the invention is better understood, the same consists in the novel features of construction, combination and arrangement of parts as will be hereinafter more fully described, illustrated in the accompanying drawing and defined in the appended claims.

In the accompanying drawing, wherein like characters of reference denote corresponding parts in the different views:

Figure 1 is a longitudinal section through a car under-frame structure having associated therewith a draft gear equipped with adapter means in accordance with the invention, the yoke of the gear being shown disposed horizontally.

Figure 2 is a bottom plan view of the assembly shown in Fig. 1; and

Figure 3 is a transverse section through the assembly shown in Fig. 1.

That part of a car under-frame structure with which the present invention particularly is concerned is comprised by a pair of laterally spaced center sills through which draft and buffing forces are transmitted to the car, while that portion of a draft gear with which the present invention particularly is concerned is comprised by the casing of a shock-absorbing mechanism which in practice is disposed in a pocket between the center sills and is supported upon a transverse carrier-plate connecting the center sills at the bottoms thereof and constituting part of said pocket.

In the drawing, the center sills are designated as 10, 10, the carrier-plate as 11, the casing of the draft gear as 12, and the horizontal yoke as 13.

As aforesaid, draft gears of specifically different designs are in use and certain of them may be used interchangeably in a certain pocket of a car under-frame structure as shown without requiring any alterations of said pocket structure. On the other hand, there are other draft gears which, as heretofore constructed, cannot be used in an under-frame pocket structure as shown,

- but require alteration of such structure in order to adapt same to accommodate them. In this connection the alteration may involve required reversal of the carrier-plate 11 or removal of the same and replacement thereof by another carrier-plate, as carrier-plates disposed at different levels have heretofore been required to properly support specifically different draft gear casings 12.
- 10 Obviously it is a time-consuming, expensive operation to reverse or to replace a carrier plate when, for any reason, it is necessary or desirable to remove a draft gear having a casing 12 of a given design and to replace it with a draft gear having a casing 12 of a specifically different design. Therefore, it is quite desirable to have a standard draft gear pocket structure including a carrier plate 11 reversal or replacement of which is unnecessary. In this connection the under-
20 frame pocket structure shown in which the carrier plate 11 has its medial portion slightly offset downwardly from the bottoms of the center sills 10, 10 may be considered as standard, as the carrier-plate thus is adapted properly to support the casings 12 of a majority of draft gears most commonly in use and, in any event, is disposed to admit into the space between the center sills 10, 10 the casings 12 of other draft gears in common use; whereas, a carrier plate 11 having its medial portion disposed at a higher elevation might deny admission of the casings 12 of some draft gears into the space between said center sills.
- The drawing illustrates by way of example a draft gear casing 12 of a well known design
35 which, in the absence of special means adapting it to be properly supported upon a standard carrier plate 11 as shown, would not be properly supported upon such carrier plate. In other words, while the casing 12 shown is provided at top and bottom thereof with laterally spaced, longitudinally extending pairs of ribs 14 the outer edges of which are parallel to the longitudinal axis of the casing to adapt the casing to be supported upon a carrier-plate for longitudinal sliding movement thereover with either the top or the bottom of the casing disposed uppermost, said ribs are of such small depth that if the casing were supported by direct engagement of either pair of said ribs upon a standard carrier plate 11 as shown, the casing would be disposed at too low an elevation. It will therefore be apparent that a casing such as the casing 12 shown, having ribs 14 of small depth, ordinarily would require for its support at a proper elevation a carrier-
45 plate 11 disposed higher than the standard carrier-plate shown. Moreover, a top strap or its equivalent would be required for cooperation with the upper edges of the top pair of ribs 14 to hold the casing against undesirable upward movements.
- 60 To adapt a casing 12 such as the one shown to be supported at a proper elevation by a standard carrier-plate 11 as shown, the said casing 12 might be provided with ribs 14 of sufficiently greater depth than the ribs shown. This, however, not only would add considerable undesirable weight to the casing, but would increase its cost, with the consequent disadvantages stated and no compensating advantages if the casing should be used in association with a vertical type yoke, in which use the ribs would be without utility. Accordingly, it is undesirable to provide a casing 12 such as the casing shown with integral ribs 14 of sufficient depth to properly support said casing upon a standard carrier-plate 11 as shown.

It is desirable, however, to provide for use with a casing 12 of the character shown, adapter means to be attached to said casing for cooperation with a standard carrier-plate 11 to support the casing 12 upon said carrier-plate at a proper elevation, and to be detached from said casing when its use is unnecessary, as when the casing is used with a vertically disposed yoke, so that the casing 12 will not, in the latter use, include excess weight. Therefore, what is contemplated by the present invention is a casing 12 of the character shown, constructed to have adapter means for the purpose stated conveniently and easily attached thereto and detached therefrom, and the provision of simple, inexpensive adapter means for the purpose stated to be attached to and detached from said casing through the instrumentality of the special construction of said casing.

In accordance with the practical embodiment of the invention illustrated in the drawing, the casing 12 is provided at or adjacent to its front end, preferably at both its top and at its bottom, although essentially only at its bottom, with a pair of laterally spaced lugs 15, 15 having alined, transverse, pin accommodating openings, while at or near its rear end it preferably, but not necessarily, is provided with a suitable socket formation, or formations, 16 longitudinally alined with and facing the pair or pairs of lugs 15, as the case may be. In other words, while the socket formation or formations 16 is or are not essential, same preferably is or are provided, and whether there shall be only a single such formation only at the bottom of the casing, or a second such formation at the top of the casing, depends upon whether there is provided only a single pair of lugs 15 at the bottom of the casing or a second pair of lugs 15 at the top of the casing. In any event, the lugs 15 and the socket formations 16 add very little weight to the casing and do not add appreciably to its production cost.

The present adapter means may comprise only one adapter element or a pair of adapter elements for use in association with any given casing 12 embodying a construction as shown and described. If two adapter elements are used they preferably are duplicates of one another. Therefore, a description of one will suffice. It consists preferably of a light-weight skeleton body portion 17 of a length to extend between a pair of the lugs 15 and the related socket formation 16 and at its rear end is provided with a suitable nib 18 to be engaged in a socket formation 16, while at its front end it is formed with a pair of transversely apertured ears 19 to fit between the lugs 15. At its inner side, said adapter element is contoured to correspond to the contour of the casing 12 so as to fit thereagainst, while at its outer side it is straight. Moreover, its inner and outer sides are related to each other so that when its inner side is fitted against the casing 12 its outer side is disposed parallel to the axis of said casing. Furthermore, said adapter element is of a thickness or depth such that, when its inner side is disposed against the casing 12, its outer side is spaced from the casing an amount such that if its outer side is engaged with a standard carrier plate 11 the casing will be supported at a proper elevation. In order that said adapter element may be of suitable width and strength and, at the same time of light weight, it preferably comprises side rails 20 connected together by cross pieces 21, with open spaces between said rails and cross pieces. It may, however, be of any

other suitable construction. In any event, to apply said adapter element to a casing 12 as shown, said adapter element simply is disposed against the casing with its nib 18 in a socket formation 16 and with its ears 19 between the related pair of lugs 15, 15. A pin 22 then is inserted through the aligned opening in said lugs and ears. The adapter element thus is securely held in assembly with the casing and yet may readily be detached therefrom simply by removing the pin 22.

When an adapter element 17 is attached to the bottom of a casing 12 as shown it provides casing means for engagement with a standard carrier plate 11 as shown to support the casing at a proper elevation upon said carrier-plate and also for such sliding movement of the casing relative to said carrier-plate as occurs in the service of the gear. On the other hand, when the use of the adapter element is not required, as for example when the casing 12 is used with a vertical yoke, it may be removed from the casing.

Obviously there is required to be used only a single adapter element 17 at the bottom of any given casing 12 to support said casing at a proper elevation upon a standard carrier-plate 11. It will be apparent, therefore, that the purpose of the present invention will be served by the provision of means for attaching only a single adapter element to the bottom of any given casing. It is preferred, however, to provide for attaching an adapter plate to either the top or the bottom of a casing 12 not only in order to render the casing reversible, but in order that, if desired, a second adapter element 17 may be attached to the top of any given casing 12 as shown in Fig. 1 for cooperation with the top flanges of the center sills 10, 10 to hold the casing against undesirable upward movements. Accordingly, and as aforesaid, casings formed in accordance with the invention preferably are provided at both top and bottom with lugs 15 and socket formations 16.

Obviously, any given adapter element would be operatively held in assembly with a casing 12 in the absence of a socket or equivalent formation 16 cooperating with the rear end of the adapter element. It is apparent, therefore, that socket formations 16 or their equivalents are not essential. They preferably are provided, however, to insure holding of the rear ends of the adapter element in proper relationship to casings 12.

Of course, in lieu of socket formations on the casing and cooperating nibs on the rear ends of the adapter elements, this arrangement might be reversed by providing nibs on the casing to cooperate with socket formations on the rear ends of the adapter elements. Likewise, there might be only a single lug on the casing to cooperate with a pair of ears on the front end of an adapter element, or only a single lug on the front end of an adapter element to cooperate with a pair of lugs on the casing. In fact, within the purview of the invention the adapter elements as well as the means for detachably mounting them upon casings 12 may take various specifically different forms.

In any case where an adapter element 17 is not used at the top of a casing 12, a cross strap 70 extending between the center sills above the casing may be provided for cooperation with the ribs 14 at the top of the casing in accordance with known practice to hold the casing against upward movements. On the other hand, the usual flange 23 at the rear end of a casing 12

as shown is of a height to cooperate with the top flanges of the center sills 10, 10 to hold the rear end of the casing against upward movement while the lugs 15 may be of proper height as shown, to cooperate with the said flanges of said center sills to hold the front end of the casing against upward movement, in which event the use of an adapter element 16 at the top of the casing obviously is unnecessary.

Preferably the adapter elements 17 are formed 10 at their inner sides to seat upon the usual ribs 14. Preferably, too, the socket formations 16 are formed by ribs cast on and extending forwardly from the usual flange 23. However, the inner faces of the adapter elements may be formed to 15 engage any other part of the casing 12 and said socket formations or their equivalents may be formed in any other suitable manner.

Without further description it is thought that the features and advantages of the invention will 20 be readily apparent to those skilled in the art, and it will of course be understood that changes in the form, proportion and minor details of construction may be resorted to, without departing from the spirit of the invention and scope of 25 the appended claims.

I claim:

1. A draft gear shock absorbing mechanism 30 casing provided near opposite ends thereof with exterior projections formed for interfitting co-operation with opposite end formations of an adapter element to be attached to said casing for the purpose of adapting said casing to be supported at a proper elevation upon the carrier-plate of a car under frame structure, an adapter 35 element having end formations for interfitting cooperation with said casing projections, and means for cooperation with one of said projections on the casing and one of said formations on the adapter element to positively, detachably 40 mount said adapter element on said casing.

2. Means to adapt the casing of the shock absorbing mechanism of a draft gear to be supported at a proper elevation upon the carrier-plate of a car under-frame structure, said means comprising an adapter element to be attached to the casing and to rest upon the carrier-plate, means carried by the casing near one end thereof and cooperating means at one end of the adapter element to be interfitted to hold said 45 end of the adapter element against outward movement and against longitudinal movement in one direction relative to the casing, means projecting from the casing near the other end thereof for cooperation with the other end of the adapter element to hold the adapter element against longitudinal movement in the opposite direction relative to the casing when said other end portions of said adapter element is engaged with said projecting means and is held against outward movement relative to the casing, and means detachably engaged with said projecting 50 means and cooperating with the said other end of the adapter element to hold the said other end of the adapter element engaged with said projecting means and against outward movement relative to the casing.

3. Means to adapt the casing of the shock absorbing mechanism of a draft gear to be supported at a proper elevation upon the carrier-plate of a car under-frame structure, said means comprising an adapter element to be attached to the casing and to rest upon the carrier-plate, means carried by the casing near one end thereof and cooperating means at one end of the adapter 55 60 65 70 75

- element to be interfitted to hold said end of the adapter element in operative relationship to the casing, apertured lug and ear formations on the casing and the adapter element at the other ends thereof, and a pin to be passed through said lug and ear formations to detachably connect the adapter element to the casing.
4. A draft gear shock absorbing casing having a recessed projection, an element to be attached to said casing to adapt the same to be supported at a proper elevation upon the carrier-plate of a car under-frame structure, a nib at one end of said element to enter the recess of said projection to hold said end of said element against outward movement relative to the casing, said projection constituting a stop for engagement with said end of said element to hold said element against longitudinal movement in one direction relative to the casing, said casing having a second projection for cooperation with the other end of said element to hold said element against longitudinal movement in the opposite direction relative to said casing when said other end of said element is engaged with said second mentioned projection and is held against out-
- ward movement relative to the casing, and means removably engageable with said second projection and the said other end of said element engaged with said second mentioned projection and to hold the said other end of said element against outward movement relative to the casing.
5. A draft gear shock absorbing casing having a recessed projection and a lug spaced from said projection, an element to be attached to said casing to adapt same to be supported at a proper elevation upon the carrier-plate of a car under-frame structure, a nib at one end of said element to enter the recess of said projection to detachably connect said end of said element to said casing, said lug engaging an opposite end portion of said element when same is operatively engaged with the casing and its nib is disposed in the recess of said projection whereby said element is held against longitudinal movement relative to the casing, and means for detachably connecting the said opposite end portion of said element to said lug and thereby detachably connecting said element to said casing.

ROBERT M. NELSON. 25
